United States Patent Office

Des. 196,343
Patented Sept. 17, 1963

196,343

AIRPLANE

James M. Norman, Atlanta, and James A. Webb, Sr.,
Smyrna, Ga., assignors to Lockheed Aircraft Corporation,
Burbank, Calif.

Filed Dec. 1, 1961, Ser. No. 67,758

Term of patent 14 years

(Cl. D71—1)

FIG. 1

FIG. 5

FIG. 2

FIG. 3

FIG. 4

FIGURE 1 is a perspective view of an airplane showing our new design;

FIGURE 2 is a top plan view thereof;

FIGURE 3 is a front elevational view thereof;

FIGURE 4 is a side elevational view thereof; and

FIGURE 5 is a rear elevational view thereof.

The side opposite that shown in FIGURE 4 is a mirror image thereof.

The essential features of the design reside in the portions shown in full lines.

We claim:

The ornamental design for an airplane, as shown and described.
